UNITED STATES PATENT OFFICE.

FRANZ TRÜB, OF ZURICH, SWITZERLAND.

GARMENT SUPPORTER.

Application filed July 23, 1924. Serial No. 727,755.

To all whom it may concern:

Be it known that I, FRANZ TRÜB, a citizen of the Republic of Switzerland, residing at Zurich, V, Konradstr. 59, in the 5 Canton of Zurich, Switzerland, have invented certain new and useful Improvements in a Garment Supporter, of which the following is a specification.

This invention relates to new and useful 10 improvements in garment supporters and has for its principal object to provide a simple and efficient device which may be readily and easily secured in position for retaining a stocking on the legs of the 15 wearer.

One of the important objects of the present invention is to provide a garment supporter of the above mentioned character, which is simple in construction, inexpensive, 20 strong and durable and furthermore adapted for the purposes for which it is designated.

A further object is to provide a garment 25 supporter formed of a single strand of wire wherein means is provided for engagement with the border of the stocking and the leg portion of the undergarment whereby the stocking will be held in proper position on the leg of the wearer.

Other objects and advantages of this 30 invention will become apparent during the course of the following description.

In the accompanying drawing forming 35 part of this specification and in which like numerals designate like parts throughout the same:

Figure 1 is a side elevation of my improved garment supporter showing the same in use.

Figure 2 is a side elevation of a modification, and

Figure 3 is a similar view of a further modification.

In the drawing wherein for the purpose of illustration is shown the preferred embodiment of my invention, the numeral 1 designates generally my improved garment supporter and the same is preferably formed of a single piece of wire in the manner to be presently described. One end of the wire is provided with a head portion such as is shown at 2 and the wire is then disposed downwardly for a suitable distance as shown at 3, thence curved upwardly as shown at 4 and directed upwardly as shown at 5. The upwardly directed portion 5 is

adapted to engage the head portion 2 so as to extend tangentially thereto and extends slightly above the head portion 2 for a suitable distance.

The upwardly directed portion 5 terminates at its upper end in the downwardly curved portion 6 and the latter is disposed downwardly as shown at 7 so as to engage the opposite side of the head 2 and extend substantially tangential thereto in the manner shown in Figure 1 of the drawing. The free end of the downwardly extending portion 7 terminates into the tapered point 8.

In use, the garment supporter is applied by inserting the pointed end 8 into the 70 border of the stocking or sock at a distance slightly inward from the upper edge of the stocking, the garment supporter is then turned in one revolution around its longitudinal axis whereby the border of the sock 75 will slide over the portions 7, 6 and 5 respectively and between the upwardly disposed portion 5 and the adjacent portion of the head 2 so as to be received in the looped portion 4.

The stocking or sock together with the supporting means therefor is then pulled slightly upward so as to enable the latter to be brought into engagement with the fabric B which comprises the leg portion of 85 the undergarment in such a manner as to cause the fabric to be disposed in the looped portion 6 in the manner clearly shown in Figure 1 of the drawing. The purpose of the provision of the pointed or tapered end 90 8 is to protect the fabric and to further facilitate the ready and easy insertion of the garment supporter through the border of the sock or stocking A and the fabric B.

In Figure 2 of the drawing a modification 95 is shown wherein the head portion 9 is in the form of an eye, otherwise the construction of the garment supporter is substantially the same as the one shown in Figure 1 and which heretofore has been more fully 100 described. In Figure 3 a still further modification is shown wherein the head portion is also formed to represent an eye 10 and a downwardly extending portion 11 thereof is disposed in a plane substantially parallel 105 to the plane of the upwardly extending portion 5. As the constructions of the garment supporter shown in the modification are substantially the same as the preferred form, and the use or application thereof is also 110

the same a further detailed description of the garment supporters shown in the modification is not thought necessary.

It will be seen from the foregoing description that a garment supporter has been provided which will obviate the necessity of having to employ the usual limb encircling band and the fastening elements associated therewith for supporting a stocking or sock on the leg of the wearer and furthermore the simplicity of my device enables the same to be easily and readily placed in use and will hold the stocking or sock in proper position and against accidental displacement. A garment supporter of the character described may be manufactured at a very low cost and will be further strong and durable and there are no parts which require adjustment.

While I have shown the preferred embodiment of my invention, it is to be understood that various changes in the size, shape and arrangement of parts may be resorted to

without departing from the spirit of the invention and the scope of the appended claim.

Having thus described my invention, what I claim is:

A garment supporter formed of a single piece of wire having a looped head portion formed at one end thereof, said wire being disposed downwardly from the head and thence curved upwardly to provide a stocking receiving loop portion, the upwardly disposed portion tangentially engaging the head portion and extending above the latter, then being curved downwardly to provide a fabric receiving loop portion, the downwardly curved portion tangentially engaging the opposite side of the head portion and terminating at its free end in a sharp point, all of said portions being disposed in the same plane.

In testimony whereof I affix my signature.

FRANZ TRÜB.
